Attorney

UNITED STATES PATENT OFFICE.

SAMUEL MURRAY, OF PORTLAND, OREGON.

STABILIZER FOR PIVOTED COUNTERWEIGHTS OF BASCULE BRIDGES.

Application filed January 6, 1925. Serial No. 850.

My invention relates to bascule bridges of the single or double leaf type, and has particular reference to an improved form of stabilizer for the pivoted counterweights usually employed in such bridges for balancing the weight of the bridge span. In the construction and operation of single or double leaf bascule bridges, it has previously been proposed to employ a heavy counterweight at the shore end of the bridge for balancing the weight of the bridge span and for assisting the bridge operating mechanism in moving the bascule leaf about its pivot or trunnions. In such constructions it is usually proposed to employ a pivoted counterweight, and to so position this counterweight that the center of mass of the same is located above, below, or at, the center of the counterweight trunnions. In those bascule bridge constructions in which the mass of the pivoted counterweight is located below the center of the counterweight trunnions, there is, of course, a tendency for the counterweight to remain in a true horizontal position throughout the movement of the bascule leaf to an open or closed position, but here the movement of such counterweights about their trunnions is due to the action of gravity, and not to any direct or positive operating mechanism. It is often advantageous to position the counterweight at or above the center of the counterweight trunnions, and in such constructions the movements of the counterweight about its trunnions must be positively controlled in order to maintain the counterweight in a horizontal position and to thus prevent the same from fouling or striking other portions of the bascule bridge structure.

An object of this invention is to provide a stabilizer for the pivoted counterweights of bascule bridges, such stabilizer functioning at all times to maintain the said counterweight in a true horizontal position throughout the operation of the bascule leaf from the open or closed position.

A further object of this invention is to provide means for mechanically interlocking the pivoted counterweight of a bascule bridge construction with the fixed supports of the bascule leaf, so that when the leaf is moved about its trunnions from an open or closed position, the pivoted counterweight will be maintained in a true horizontal position, and will have an angular displacement

equal to that of the leaf but in an opposite direction.

A still further object of this invention is to provide a device of this general character that is simple in construction, inexpensive to manufacture, reliable in operation, and highly efficient in the purposes for which designed.

In the accompanying drawings forming a part of this specification and in which like numerals are employed to designate like parts throughout the several views:

Figure 1 is a fragmental side elevation of one form of bascule bridge, showing a pivoted counterweight and my improved stabilizing device applied thereto.

Figure 2 is a plan view of the same,

Figure 3 is an enlarged view of a portion of the bascule leaf truss and counterweight, showing a detail of construction,

Figure 4 is a side elevation of a modified form of bascule bridge, showing the counterweight mounted above the center of its trunnions, and showing my improved stabilizing device applied thereto, and,

Figure 5 is an enlarged fragmental view, partly in section, of the form of bascule bridge and counterweight stabilizer shown in Figure 4.

Referring to the drawings, wherein for the purpose of illustration is shown several preferred embodiments of my invention, the numerals 1 and 2 designate the usual masonry standards or supports fixed at or near the shore line, and having the upwardly extending columns 3 and 4, at the upper ends of which are the main bearings 5 and 6. Extending between the columns 3 and 4 and journaled within the bearings 5 and 6, is a transverse shaft 7, passing through the main side trusses 8 and 9 of a bascule leaf of any suitable form, and constituting the pivot or trunnions about which the bascule leaf rotates during the opening or closing movements. The rack and pinion gearing usually employed for operating bridges of this character has been omitted from the drawings for the sake of clearness of illustration. All of the above described construction of bascule leaf and supports is old and well known in the art and forms no part of the present invention.

Referring to the disclosure of Figures 1, 2 and 3 of the accompanying drawings, the numeral 10 designates a counterweight of

stone, concrete, metal or other suitable material, made of sufficient size and weight to properly balance the bridge span. Passing through the counterweight 10 at the center of mass of the same, is a shaft 11 extending beyond the side faces of the counterweight, and rotatably mounted within suitable bearings 12 and 13 carried by the main side trusses 8 and 9 respectively. Fixed bevelled segmental racks 14 are rigidly secured to the sides of the pivoted counterweight 10, the said racks lying concentrically about the pivot or trunnions of the said pivoted counterweight.

15 Fixed bevelled segmental racks 15 are rigidly secured to the inner faces of the columns 3 and 4, the said racks lying concentrically about the main trunnion or shaft 7 of the bascule leaf or span. Bevelled gears or pinions 16 and 17 are keyed or otherwise secured to the ends of an interlocking shaft 18 lying on a line connecting the main bridge trunnions and the counterweight trunnions and mounted in suitable bearings 19, secured to the outer sides of the main side trusses 8 and 9. The bevelled gears 16 and 17 extend through suitable openings in the main side trusses 8 and 9 and operatively engage the segmental racks 14 and 15 respectively. While I have illustrated the racks, shafts and pinions applied to both sides of the counterweight, such double construction is not always required, and the stabilizer will function equally well 35 if the racks, shafts and pinions are attached to one side only of the counterweight.

Referring to the operation of the bascule bridge and pivoted counterweight disclosed in Figures 1, 2 and 3 and specifically described above, it is obvious that as the bascule leaf or span is moved about its pivotal mounting from a closed or open position, the stationary racks 15 will cause a rotation of the pinions 17. The rotation imparted to the pinions 17 will cause a corresponding rotation of the interlocking shafts 18 and the gears or pinions 16, which rotation will cause the pinions 16, because of their engagement with the segmental racks 14, to move the pivoted counterweight about its pivots or trunnions.

Referring to the disclosure of Figures 4 and 5 of the accompanying drawings, wherein is shown a bascule bridge construction in which the center of mass of the counterweight is located above the center of the counterweight pivot or trunnions, the overhead counterweight 20 is supported above the plane of the main side trusses 8 and 9 by means of suitable supports or standards 21, the lower ends of which are pivotally mounted on a transverse shaft 22, extending between the main side trusses 8 and 9. A fixed bevelled segmental rack 23 is rigidly attached to the standards 21 and is posi-

tioned concentrically about the pivot or trunnions of the said standards. A fixed bevelled segmental rack 24 is rigidly secured to the inner face of the column 3, the said rack being positioned concentrically about the main trunnions or shaft 7 of the bascule leaf or span. Bevelled gears 25 and 26 are keyed or otherwise secured to the ends of an interlocking shaft 27 lying in a line connecting the main bridge trunnions and the trunnions of the standards 21, and rotatably mounted in suitable bearings 28, secured to the outer faces of the main side truss 8. The bevelled gears 25 and 26 extend through suitable openings in the main side truss 8 and operatively engage the segmental racks 23 and 24 respectively. While I have illustrated the racks, shaft and pinions applied to one side only of the counterweight, it is obvious that such mechanisms could be duplicated and the stabilizer applied to both sides of the pivoted counterweight.

Referring to the operation of the form of bascule leaf and overhead counterweight shown in Figures 4 and 5, and specifically described in the preceding paragraph, it is obvious that as the bascule leaf or span is moved about its pivotal mounting from an open or closed position, the stationary rack 24 will cause a rotation of the pinion 26, which rotation will cause a corresponding rotation of the interlocking shaft 27. Rotation of the shaft 27 will cause the pinion 25 to ride upwardly along the segmental rack 23 to move the standards 21 and the counterweight 20 carried thereby about the pivot or trunnions of the standards 21.

By selecting the proper gear ratio for the several racks and pinions described in connection with the disclosures of Figures 1 to 5 inclusive, the counterweights will have the same angular movement about their pivot or trunnions as the bascule leaf or span has about its main pivot or trunnions but in a reverse direction, and, therefore, the counterweights will always remain in a true horizontal plane in all positions of the bascule leaf or span.

In the event that the center of mass of the counterweight is suspended below its pivot or trunnions, there of course would be a natural tendency for the counterweight to remain in a horizontal position during the movements of the bascule leaf or span. The stabilizer above described is, however, of great advantage in such construction, as it forms a positive connection between the moving bridge parts and the pivoted counterweight and so controls the movement of the counterweight that the swinging and vibration of the bridge structure will not cause erratic movements of the counterweight, and will present the same from striking or fouling other portions of the

movable bascule span or its associated parts.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described my invention, I claim:—

1. In a bascule bridge, the combination of a main bascule span, fixed supports on which the span is pivotally mounted, a rack secured to the fixed supports, a pivoted counterweight carried at the shore end of the span, a rack secured to the counterweight, and gearing interposed between the said racks for moving the counterweight about its pivotal mounting as the span is moved to open or closed position.
2. In a bascule bridge, the combination of a main bascule span, fixed supports on which the span is pivotally mounted, a segmental rack secured to the fixed supports, a pivoted counterweight carried at the shore end of the span, a segmental rack secured to the counterweight, and gearing interposed between the two segmental racks for moving the counterweight about its pivotal mounting to maintain the counterweight in a horizontal position throughout the opening and closing movements of the bridge.
3. In a bascule bridge, the combination of a main bascule span, fixed supports on which

the span is pivotally mounted, a segmental bevelled rack secured to the fixed supports and disposed concentrically about the main span trunnions, a pivoted counterweight carried at the shore end of the span, a segmental bevelled rack secured to the counterweight and disposed concentrically about the counterweight trunnions, a bevelled pinion operatively engaging each of said segmental racks, and driving means interposed between the said pinions for moving the counterweight about its pivotal mounting as the span is moved to open or closed position.

4. In a bascule bridge, the combination of a main bascule span, fixed supports on which the span is pivotally mounted, a segmental rack secured to the fixed supports and disposed concentrically about the main span trunnions, a pivoted counterweight carried at the shore end of the span, a segmental rack secured to the counterweight and disposed concentrically about the counterweight trunnions, a pinion operatively engaging each of said segmental racks, and a shaft operatively connecting each of said pinions and lying in a line connecting the main span trunnions and counterweight trunnions whereby the movement of the span about its trunnions is transmitted to the counterweight to maintain the same in horizontal position throughout the opening and closing movements of the bridge.

In testimony whereof I hereunto affix my signature.

SAMUEL MURRAY.
